MULTIPLE POSITION RECLINING CHAIR
Fritjof F. Schliephacke, Berlin-Schmargendorf, Germany, assignor to Anton Lorenz, Boynton Beach, Fla.

Filed Jan. 28, 1963, Ser. No. 254,175
10 Claims. (Cl. 297—89)

The present invention relates to improvements in reclining chairs and in particular to a novel and improved seat control arrangement and leg-rest control arrangement for reclining chairs of the multiple position type.

In multiple position reclining chairs, the body-supporting structure formed by the seat and back-rest is movable in a first motion phase from an upright sitting position to an intermediate, tilted sitting position, and then through a second motion phase to a reclining or fully-tilted position. A leg-rest is also provided with control means to move the leg-rest from a retracted position beneath the seat to an extended position forwardly of the seat in response to movement of the body-supporting structure from the upright sitting position to the intermediate, tilted sitting position. Thus, in the latter position, while the occupant's body is still substantially upright but slightly tilted and is properly disposed for reading, viewing television or the like, the occupant's legs are comfortably supported in outstretched condition by the extended leg-rest. The leg-rest control means are also adapted to maintain the leg-rest in elevated position relative to the seat when the body-supporting structure is moved through the second motion phase to the reclining position.

In many multiple position reclining chairs, the leg-rest control arrangement is entirely independent of the arrangement which controls the movement of the body-supporting structure. This renders it difficult to properly coordinate the movements of the leg-rest in the various motion phases in such a manner that the leg-rest is properly positioned throughout the second motion phase and especially at the reclining or fully-tilted position. In the latter position, it is essential that the leg-rest be not over-elevated to a position past a horizontal attitude, and at the same time that it be extended far enough to comfortably support the occupant's outstretched legs.

In accordance with the invention there is provided a multiple position reclining chair in which a body-supporting structure is mounted on a support frame by front and rear guide links. The rear guide link is mounted directly on the support frame while the front guide link is mounted on a carrier linkage which includes as movable links first and second carrier links and an intermediate link pivotally connected between the free ends of the carrier links and facing the leg-rest in the upright sitting position. At least one of the carrier links is pivotally mounted on the rear guide link, such that this mounted carrier link is drawn rearwardly during the first motion phase as the rear guide link turns rearwardly. This rearward movement of the carrier link turns the intermediate link for positive actuation of the leg-rest through an actuating link which connects the intermediate link to the leg-rest mounting linkage. In the second motion phase, the rear guide link is blocked from further rearward movement, and the carrier linkage becomes a four-bar linkage which moves upwardly from its supported position as the body-supporting structure turns about its pivotal connection with the stationary rear guide link.

Additional objects and advantages of the invention will become apparent during the course of the following specification when taken in connection with the accompanying drawings, in which:

An object of the present invention is to provide in a multiple position chair a carrier linkage serving as a sup-

2

port for the front guide link of the chair. The carrier linkage is also operatively connected to the leg-rest of the chair. In the first motion phase, at least a portion of the carrier linkage is moved rearwardly in the chair in such a manner as to provide a positive actuation force for the leg-rest, whereby to elevate the leg-rest to its extended position.

Another object of the invention is the provision of a carrier linkage of the character described which is also adaptable for selective arrangement in such a manner as to move the leg-rest to an adjusted extended position in the second motion phase of the chair.

FIG. 1 is a side elevational view, with parts broken away and shown in section, of a reclining chair incorporating the seat control and leg-rest control arrangements of the present invention, the chair being shown in an upright sitting position;

FIG. 2 is a side elevational view similar to FIG. 1, but showing the chair in an intermediate, tilted sitting position;

FIG. 3 is a side elevational view similar to FIGS. 1 and 2, but showing the chair in a fully-tilted or reclined position;

FIG. 4 is a side elevational view, with portions broken away and shown in section, of a reclining chair incorporating a modified type of control arrangement made in accordance with the invention, the chair being shown in its upright sitting position;

FIG. 5 is a side elevational view similar to FIG. 4, but showing the chair in its intermediate, tilted sitting position;

FIG. 6 is a side elevational view similar to FIGS. 4 and 5, but showing the chair in its fully-tilted or reclined position;

FIG. 7 is a side elevational view, with portions broken away and shown in section, of a reclining chair incorporating a further modification in the control arrangement of the invention, the chair being shown in its upright sitting position;

FIG. 8 is a side elevational view similar to FIG. 7, but showing the chair in its intermediate, tilted sitting position; and

FIG. 9 is a side elevational view similar to FIGS. 7 and 8, but showing the chair in its fully tilted or reclined position.

Referring now in detail to the drawings, and in particular to FIGS. 1-3, there is shown a reclining chair incorporating the inventions herein and designated generally by the reference numeral 10. The structure of chair 10 includes a support frame generally designated by reference numeral 12 and having opposed side walls 14 and 16 interconnected by suitable cross-braces 18, 20 and 22. The chair 10 also includes a body-supporting structure generally designated by the reference numeral 24 and including a seat 26 and a back-rest 28 formed integrally as a rigid unit. The body-supporting structure 24 is mounted on the support frame 12 by a front guide link 30 and a rear guide link 32 for movement from the upright sitting position of FIG. 1 to the intermediate, tilted sitting position shown in FIG. 2 and then to the fully-tilted or reclined position shown in FIG. 3.

At its lower end, the rear guide link 32 has a fixed pivotal mount 36 on the support frame 12, and at its upper end is connected by pivot 38 to the rear portion 65 of the seat 26. The front guide link 30 is connected by pivot 40 to the seat 26 at a point spaced forwardly of the pivotal connection 38. The lower end of the front guide link 30 is mounted on a carrier linkage which includes a first carrier link 42, a second carrier link 44, and an intermediate link 46. The rear end of the first carrier link 42 is mounted by pivot 48 on the lower portion of rear guide link 32, and the forward end thereof is con-

nected by a pivot 50 to the lower end of the intermediate link 46. The rear end of the second carrier link 44 is mounted by pivot 52 on the support frame at a point spaced above and forwardly of the pivotal mount 48. The forward end of the second carrier link 44 is connected by pivot 54 to the intermediate link 46 at a point above the pivot 50. In the upright sitting position of FIG. 1, both carrier links 42 and 44 extend forwardly from their respective pivotal mounts 48 and 52, with the second carrier link 44 overlying the first carrier link 42 and being spaced thereabove, and with the first carrier link 42 slidably supported by a roller 58 mounted on cross-bar 18.

As was previously indicated, the first carrier link 42, second carrier link 44, and intermediate link 46 serve as three movable links of a carrier linkage which, during the first motion phase, constitutes a compound linkage. This compound linkage includes, in addition to the aforementioned three movable links, the portion of the rear guide link 32 between pivots 36 and 48, and as a stationary link thereof, the portion of the support frame 12 between the fixed pivots 36 and 52. The front guide link 30 is mounted on this compound linkage, in the embodiments of FIGS. 1-3 the front guide link, for example, being connected to the second carrier link 44 by pivot 56.

The chair 10 also includes a leg-rest 60 and a leg-rest mounting linkage, generally designated by reference numeral 62, which is adapted to guide the leg-rest between a retracted position beneath the seat to an elevated, leg-supporting position forwardly of the seat in response to movement of the body-supporting structure 24. This leg-rest mounting linkage 62 may be of any conventional type, but for purposes of illustration, is shown a double four-bar or lazy tongue type of linkage. Specifically, the leg-rest mounting linkage 62 includes a first pair of mounting links 64 and 66 having a pivotal connection 68 at their adjacent ends and a second pair of mounting links 70 and 72 having a pivotal connection 74 at their adjacent ends. The mounting link 64 has a pivotal mount 76 at its upper end on the seat 26, while the mounting link 70 has a pivotal mount 78 on the seat 26, which is spaced rearwardly from the pivotal mount 76. Intermediate its ends, the mounting link 64 crosses over the mounting link 72 and has a pivotal connection 80 thereto at the crossing-over point. The mounting link 66 has a pivotal connection 82 at its forward end to the leg-rest 60, while the mounting link 72 has a pivotal connection 84 at its forward end to the leg-rest 60 at a point spaced from the pivotal connection 82.

Actuating means are provided for elevating the leg-rest 60 during the first motion phase from the retracted position shown in FIG. 1 to the extended leg-supporting position shown in FIG. 2. Such actuating means includes an extension 86 of the intermediate link 46 extending beyond the pivot 54, and an actuating link 88 connected to said extension 86 by a pivot 90. The opposite end of the actuating link 88 is connected by pivot 92 to the leg-rest mounting link 70 at a point spaced below the pivotal mount 78 of said link 78.

In the upright sitting position of FIG. 1, the first carrier link 42 rests upon the roller 58 in a substantially horizontal position, so that the compound carrier linkage formed by the carrier links 42, 44, the intermediate link 46 and the lower portion of the rear guide link 32 serve as a stationary portion of the support frame 12. The rear guide link 32 extends vertically upward from its pivotal mount 36 and engages a stop member 59 affixed to support frame 12, the latter preventing forward movement of the seat. The front guide link 30 extends upwardly and forwardly from its pivotal mount 56 to the seat 26. The body-supporting unit 24 is therefore supported in the level sitting position of FIG. 1. The leg-rest mounting links 64 and 70 extend downwardly from their respective pivotal mounts 76 and 78 on the seat 26, thereby positioning the leg-rest 60 in its retracted position in which it is substantially vertically disposed beneath the forward

end portion of the seat 26. The leg-rest actuating link 88 extends forwardly and downwardly from their respective pivotal mounts 76 and 78 on the seat 26, thereby positioning the leg-rest 60 in its retracted position in which it is substantially vertically disposed beneath the forward end portion of the seat 26. The leg-rest actuating link 88 extends forwardly and downwardly from the intermediate link extension 86 to the mounting link 70.

When the occupant of the chair in the upright sitting position of FIG. 1 wishes to assume a more comfortable sitting position with his legs supported in outstretched condition, he applies rearward pressure against the body-supporting structure 24. The body-supporting structure then moves rearwardly through a first motion phase, guided by the front guide link 30 and rear guide link 32, which turn rearwardly in unison. During this first motion phase the first carrier link 42 remains supported by the cross-bar 18, although it rolls therewith as will be presently described. The second carrier link 44, however, remains substantially immovable, serving as a fixed portion of the support frame to support front guide link 30. Said front guide link 30 turns rearwardly and upwardly about its pivotal mount 56 upon second carrier link 44, to guide the forward portion of the seat 26 rearwardly and also to elevate the same slightly. At the same time, the rear guide link 32 turns rearwardly and downwardly upon its pivotal mount 36 on the support frame 12 to guide the rear portion of the seat 26 rearwardly and also to lower it slightly. Thus, in the intermediate, tilted sitting position of FIG. 2, the body-supporting structure 24 has moved rearwardly from its position of FIG. 1 and has also been slightly tilted, although it is still in a substantially sitting position whereby the occupant's body is still upright and is properly disposed for viewing television, reading, or the like.

As the rear guide link 32 turns rearwardly during the first motion phase, it carries with it the first carrier link 42, which is drawn rearwardly along roller 58. This rearward sliding movement of carrier link 42 draws the lower end of intermediate link 46 rearwardly, causing said intermediate link 46 to turn in a counter-clockwise direction (as viewed in FIGS. 1 and 2) about its pivotal mount 54 on the stationary second carrier link 44. The upper extension 86 of the intermediate link 46 thus moves forwardly to actuate the leg-rest as will be presently explained.

During the first motion phase, the leg-rest 60 and the leg-rest mounting linkage 62 is carried rearwardly with the forward portion of the seat through the pivotal mounts 76 and 78, relative to the support-frame 12. Since the actuating link 88 is pivotally mounted on the forwardly-moving extension 86 of intermediate link 46, said actuating link 88 exerts a pushing force at point 92 against the leg-rest mounting link 70, thereby expanding the leg-rest mounting linkage 62 and moving the leg-rest 60 to its extended, leg-supporting position of FIG. 2. In this position, the leg-rest 60 is located forwardly of the front end of the seat 26 and is substantially at the level thereof, in proper position to comfortably support the outstretched legs of the occupant. In actuating the leg-rest mounting linkage 62, the actuating link 88 turns upwardly about its pivotal mount 90, as can be seen from a comparison of FIGS. 1 and 2.

The intermediate, tilted sitting position of FIG. 2 is determined by engagement of the rear guide link 32 with the cross-bar 20. This halts further simultaneous rearward pivoting movement of the guide links 30 and 32, and constrains further movement of the body-supporting structure 24 to a pivoting movement about another center of rotation through a second motion phase, in a manner to be presently described.

When the occupant of the chair wishes to assume a more comfortable position for optimum relaxation, he applies further rearward pressure against the body-supporting structure 24. Since the rear guide link 32 is now

restrained from further rearward turning movement by its engagement with the cross-bar 20, further rearward movement of the body-supporting structure 24 is now limited to turning movement about its pivotal connection 38 with the stationary rear guide link 32. During this second motion phase, the forward portion of the seat 26 is elevated, carrying upwardly with it the front guide link 30, which in turn raises the second carrier link 44, as well as the intermediate link 46 and the first carrier link 42. Since the rear guide link 32 is now immovable, the pivotal mount 48 of the first carrier link 42 is now stationary, and the linkage formed by the carrier links 42, 44 and the intermediate link 46 now functions as a four-bar linkage with the portion of the support frame 12 between pivots 48 and 52 constituting the immovable link thereof. Since the first carrier link 42 has a greater length than the second carrier link 44, the free end of the former travels through a greater arc than the free end of the second carrier link 44 so that the pivot 50 moves upwardly and rearwardly relative to the pivot 54. This results in the intermediate link 46 being turned in a forward or counter-clockwise direction about the pivot 54 as the intermediate link 46 is raised by the carrier links 42 and 44. Consequently, its top pivot 90 at the end of extension 86 moves in an upward direction following the turning movement of the body-supporting structure and is also moved forwardly away from the pivotal mount 48.

The elevating movement of the four-bar linkage raises the left-rest linkage through the actuating link 88, but not in itself to the extent necessary to cause the leg-rest linkage to keep up with the upward movement of the front of the seat. Hence, the movement of the leg-rest linkage would tend to lag behind the seat movement in the second motion phase with the result that the leg-rest would move downwardly relative to the forward end of the seat in the fully-reclined position. The forward movement of the upper end of intermediate link 46, however, compensates for this lag in leg-rest movement. The counter-clockwise turning movement of the intermediate link 46 provides an additional forward movement to the actuating link 88 which elevates the leg-rest mounting linkage 62 to substantially the same extent as the forward end of the seat 26. Thus, in the fully-tilted or reclined position of FIG. 3, the leg-rest 69 is located at approximately the same level and angle relative to the forward end of the seat as it is in the intermediate, tilted sitting position of FIG. 2.

The arrangement of the linkage formed by the carrier links 42, 44 and intermediate link 46 may be selectively varied to produce other desired adjustments of the leg-rest 60 in the fully-reclined position. Since the relative lengths of the carrier links 42 and 44 determine the degree of rotation of the intermediate link 46, these lengths can be varied to cause the leg-rest to be located at higher or lower level in the fully-reclined position, depending upon the comfort requirements of the particular chair in which the linkage is employed.

The end of the second motion phase is established by engagement of the rear portion of the body-supporting structure 24 with the cross brace 22, the structure 24 being then disposed in the fully-tilted position of FIG. 3. To return to the intermediate position of FIG. 2, it is only necessary for the occupant to shift his weight forwardly. To return from the intermediate position to the upright sitting position of FIG. 1, the occupant exerts downward pressure upon the leg-rest and urges his weight further forwardly by grasping the side frames 14 and 16.

Referring now specifically to FIGS. 4 through 6, there is shown a reclining chair incorporating a modified form of control mechanism made in accordance with the invention herein and designated generally by the reference numeral 110. The chair 110 again includes a support frame 112 having opposed side walls 114 and 116 interconnected by suitable cross-braces 118, 120, and 122, and a body-supporting structure 124 including an integrally-formed seat 126 and back-rest 128. The body-supporting

structure 124 is mounted on the support frame 112 by a front guide link 130 and a rear guide link 132 for movement from the upright sitting position of FIG. 4 to the intermediate, tilted sitting position shown in FIG. 5 and then to the fully-tilted or reclined position shown in FIG. 6.

The rear guide link 132 is again provided with a fixed pivotal mount 136 on the support frame 112, and a pivotal connection 138 to the rear portion of the seat 126. The front guide link 130 is connected by pivot 140 to the seat 126 at a point spaced forwardly of the pivotal connection 138. A carrier linkage is again provided for supporting the front guide link 130, this carrier linkage again including a first carrier link 142, a second carrier link 144, and an intermediate link 146. The rear end of the first carrier link 142 is again mounted by pivot 148 on the rear guide link 132, and the forward end thereof is connected by a pivot 150 to the lower end of the intermediate link 146. The rear end of the second carrier link 144 in this instance is also mounted on the rear guide link 132 by pivot 152 at a point spaced above the pivotal mount 148. The forward end of the second carrier link 144 is connected by pivot 154 to the intermediate link 146 at a point thereon spaced above the pivot 150. The intermediate link 146 in this instance has a long extension portion 186 projecting above the pivot 154.

The carrier links 142 and 144 are, in this embodiment, substantially the same size and in the upright sitting position of FIG. 4, both carrier links 142 and 144 extend forwardly and slightly downwardly from their respective pivotal mounts 148 and 152.

The carrier linkage, formed by the carrier links 142 and 144, as well as intermediate link 146 and rear guide link 132 is again movable during the first motion phase, and again serves as a support for the front guide link 130 which is mounted by pivot 156 on the second carrier link 144.

The chair 110 again includes a leg-rest 160 carried by a leg-rest mounting linkage 162 for movement between the retracted position of FIG. 4 and the extended positions of FIGS. 5 and 6. The leg-rest mounting linkage 162 is generally similar to that shown in FIGS. 1-3, and includes a first pair of mounting links 164 and 166 having a pivotal connection 168 at their adjacent ends and a second pair of mounting links 170 and 172 having a pivotal connection 174 at their adjacent ends. The upper ends of mounting links 164 and 170 are respectively mounted by pivots 176 and 178 at spaced points on the seat 126. Intermediate their ends, the mounting links 164 and 172 cross each other and are connected by pivot 180 at their crossing-over point. The mounting links 166 and 172 are connected to spaced points on leg-rest 160 by respective pivots 182 and 184.

Means are again provided for actuating the leg-rest mounting linkage 162 in such a manner as to elevate the leg-rest 160 during the first motion phase from the retracted position shown in FIG. 4 to the extended leg-supporting position shown in FIG. 5. Such actuating means comprises an extension 171 of leg-rest mounting link 170 which projects above the pivotal mount 178 and an actuating link 188 connected at one end by pivot 192 to the extension 171 of mounting link 170, and connected at its other end to the top end of intermediate link extension 186.

In the upright sitting position of FIG. 4, the first carrier link 142 again rests upon a roller 158 carried by the cross-bar 118. The rear guide link 132 is upstanding from its pivotal mount 136, and the front guide link 130 extends upwardly and forwardly from its pivotal mount 156 toward the seat 126, engaging a stop member 159 fixed to the second carrier link 144 so as to prevent the body-supporting structure from moving forwardly. The leg-rest 160 is supported by the leg-rest linkage 162 in a retracted position beneath the forward portion of seat 126.

When the occupant of the chair in the upright sitting

position of FIG. 4 applies rearward pressure against the body-supporting structure 124, the body-supporting structure moves rearwardly through a first motion phase, guided by the rear guide link 132 and front guide link 130, the rear guide link about its pivotal mount 136 on the support frame 112. During this first motion phase, the second carrier link 144 as well as the first carrier link 142 moves rearwardly, being drawn in this direction by the rear guide link 132. Thus the pivotal mount 156 of the front guide link is moved rearwardly with the second carrier link 144, and the front guide link 130 turns only slightly about said pivotal mount 156. In the intermediate, tilted sitting position of FIG. 5, the body-supporting structure 124 has moved rearwardly from its position of FIG. 4 and has also been slightly tilted by action of the guide links 130 and 132, although it is still in a substantially sitting position with the occupant's body supported in upright condition and properly disposed for viewing television, reading, or the like.

As the carrier linkage moves rearwardly, the first carrier link 142 moving along roller 158, the intermediate link 146 is moved rearwardly therewith and is also turned in a clockwise direction, as can be seen by a comparison of FIGS. 1 and 2. The upper end of the intermediate link extension 186 is thus moved rearwardly relative to seat 126.

During the first motion phase, the leg-rest 160 and the leg-rest mounting linkage 162 is carried rearwardly with the forward portion of the seat through the pivotal mounts 176 and 178. Because of the turning action of intermediate link 146, its extension 186 exerts a pulling force on the extension 171 of leg-rest mounting link 170 through actuating link 188. The mounting link 170 therefore turns about its pivotal mount 178, thereby elevating the leg-rest 160 to its extended, leg-supporting position of FIG. 5. In this position, the leg-rest 160 is located forwardly of the front end of the seat 126 and is substantially at the level thereof, in proper position to comfortably support the outstretched legs of the occupant.

The intermediate, tilted sitting position of FIG. 5 is determined by engagement of the rear guide link 132 with the cross-bar 120, the latter halting further simultaneous rearward pivoting movement of the guide links 130 and 132.

When the occupant of the chair applies further rearward pressure against the body-supporting structure 124, the rear guide link 132 is restrained from further rearward turning movement by its engagement with the cross-bar 120, and further rearward movement of the body-supporting structure 124 is limited to turning movement about its pivotal connection 138 with the stationary rear guide link 132. During this second motion phase, the forward portion of the seat 126 is elevated, carrying upwardly with it the front guide link 130 which in turn raises the second carrier link 144 and through it the first carrier link 142 and intermediate link 146, said carrier links turning about their respective pivotal mounts 148 and 152 on the stationary rear guide link 132. During the second motion phase, the carrier linkage serves as a four-bar linkage with the carrier links 142, 144 and the intermediate link 146 constituting the movable links, while the portion of stationary rear guide link 132 between pivots 148 and 152 constitutes the fixed link. Since the carrier links 142 and 144 are substantially parallel, the four-bar linkage operates essentially as a parallelogram. As the intermediate link 146 is lifted, therefore, it is maintained at approximately the same angular disposition relative to the support frame. However, since the upwardly turning seat 126 carries the leg-rest mounting linkage 162 in an arcuate path with a rearward component of movement, the effect is that the pivot point 190 at the top of intermediate link 146 moves forwardly relative to the leg-rest mounting linkage 162 and exerts a pushing force upon the link extension 171 through actuating link 188. This results in the leg-rest 160 being

slightly lowered relative to the front of the seat during the second motion phase.

The fully-tilted or reclined position of FIG. 6 is reached when the rear portion of the body-supporting structure 125 engages and is stopped by the cross-brace 122. To return to the upright sitting position of FIG. 4, the occupant shifts his weight forwardly to bring the body-supporting structure to the intermediate, tilted sitting position, and then applies downward pressure on the leg-rest to return the structure to the upright sitting position.

FIGS. 7 through 9 illustrate another reclining chair 210 having a modified form of structure made in accordance with the invention herein. The chair 210 includes a support frame 212 having opposed side walls 214 and 216 interconnected by suitable cross-braces 218, 220 and 222. The body-supporting structure 224 of chair 210 includes a seat 226 and a back-rest 228 formed integrally with each other to provide a rigid unit. The body-supporting structure 224 is mounted by front guide link 230 and a rear guide link 232 for movement from the upright sitting position of FIG. 7 to the intermediate, tilted sitting position of FIG. 8 and then to the fully-tilted position of FIG. 9.

The rear guide link 232 is mounted by pivot 236 on the support frame 212, and is connected by pivot 238 to the rear portion of the seat 226. The front guide link 230 is connected by pivot 240 to the seat 226 at a point spaced forwardly of the pivotal connection 238. The lower end of the front guide link 230 is mounted by pivot 256 on the intermediate portion of a first carrier link 242 which forms a portion of the carrier linkage together with a second carrier link 244, and an intermediate link 246. The rear ends of the carrier links 242 and 244 are respectively mounted by pivots 248 and 252 at spaced points on the rear guide link 232. In this instance the carrier links 242 and 244 are crossed so that the forward end of the first carrier link 242 is connected by a pivot 250 to an intermediate point on the intermediate link 246, while the forward end of the second carrier link 244 is connected by pivot 254 to the intermediate link 246 at a point spaced below the pivot 250. In the upright sitting position of FIG. 7, both carrier links 242 and 244 extend forwardly from their respective pivotal mounts 248 and 252, and cross each other approximately at their centers.

The chair 210 also includes a leg-rest 260 and a leg-rest mounting linkage 262 for guiding the leg-rest between a retracted position beneath the seat to an elevated leg-supporting position forwardly of the seat in response to movement of the body-supporting structure 224. The leg-rest mounting linkage 262 is similar to those previously described and includes a first pair of mounting links 264 and 266 connected at their adjacent ends by pivot 268, and a second pair of mounting links 270 and 272 having a pivotal connection 274 at their adjacent ends. The mounting links 264 and 270 are mounted by respective pivots 276 and 278 at spaced points on the seat 226. The mounting link 264 crosses over the mounting link 272 and has a pivotal connection 280 thereto at the crossing-over point. The mounting links 266 and 272 are connected to spaced points on the leg-rest 260 by respective pivots 282 and 284.

Actuating means are provided for elevating the leg-rest 260 during the first motion phase from the retracted position shown in FIG. 7 to the extended leg-supporting position shown in FIG. 8. Such actuating means include an extension 286 of the intermediate link 246 extending above the pivot 250, and an actuating link 288 connected to said extension 286 by pivot 290. The forward end of the actuating link 288 is connected by pivot 292 to the leg-rest mounting link 270 at a point spaced below the pivotal mount 278 of said link 270.

In the upright sitting position of FIG. 7, the second carrier link 244 rests upon a roller 258 affixed to the support frame 212. The rear guide link 232 extends vertically upward from its pivotal mount 236, and the front

guide link 230 extends upwardly and forwardly from its pivotal mount 256 toward its pivotal connection 240 with the seat 226. The leg-rest mounting links 264 and 270 extend downwardly from their respective pivotal mounts 276 and 278 on the seat 226, thereby positioning the leg-rest 260 in its retracted position beneath the forward end portion of the seat 226. The leg-rest actuating link 288 extends forwardly and slightly downwardly from the intermediate link extension 286 toward the mounting link 270.

When the occupant of the chair in the upright sitting position of FIG. 7 applies rearward pressure against the body-supporting structure 224, the latter moves rearwardly through the first motion phase, guided by the front guide link 230 and rear guide link 232. During this first motion phase, as the rear guide link 232 turns rearwardly, the crossed carried links 242, 244 cause a reverse movement of the intermediate link 246 so that the latter turns in a forward or counter-clockwise direction. Thus, the intermediate link extension 286 is moved forwardly and exerts a forward force on the leg-rest mounting linkage, through actuating link 288, to elevate the leg-rest 260 to its extended position.

The intermediate, tilted sitting position of FIG. 8 is determined by engagement of the rear guide link 232 with the cross-bar 220. This halts further simultaneous rearward pivoting movement of the guide links 230 and 232, and constrains further movement of the body-supporting structure 224 to a turning movement about pivot 238 in the second motion phase.

When the occupant of the chair 210 in the intermediate position of FIG. 8 applies further rearward pressure against the body-supporting structure 224, the latter moves in the second motion phase. The rear guide link 232 is restrained from further rearward turning movement by its engagement with the cross-bar 220, and further rearward movement of the body-supporting structure 224 is now limited to turning movement about its pivotal connection 238 with the stationary rear guide link 232.

During this second motion phase, the forward portion of the seat 226 is elevated, carrying upwardly with it the front guide link 230 which in turn raises the first carrier link 242 and thus the four-bar linkage formed by the carrier links 242, 244 and the stationary rear guide link 232. In this instance the first carrier link 242 has a shorter length than the second carrier link 244, so that, as the intermediate link 146 is elevated by the carrier links, it is also turned slightly in a rearward or clockwise direction. As a result, the leg-rest 260 is retained in its extended position forwardly of the seat 226, but is adjusted slightly downwardly and outwardly in the fully-reclined position of FIG. 9.

While preferred embodiments of the invention have been shown and described herein, it is obvious that numerous additions, changes and omissions may be made in such embodiments without departing from the spirit and scope of the invention.

What I claim is:

1. A multiple position reclining chair comprising a support frame, a body-supporting structure including a seat and back-rest, control means mounting the body-supporting structure on the support frame for rearward movement through a first motion phase from a sitting position to an intermediate, tilted sitting position and through a second motion phase to a reclining position, said control means including front and rear guide links pivotally connected to spaced points on the seat, the rear guide link having a pivotal mount on the support frame, and a carrier linkage mounting the front guide link, said carrier linkage including a pair of carrier links extending forwardly of the chair and an intermediate link pivotally connected to the forward ends of said carrier links and extending therebetween, at least one of said carrier links being pivotally mounted on the rear guide link, said

one carrier link being slidably mounted on said support frame for longitudinal movement during said first motion phase, a leg-rest, a leg-rest mounting linkage carrying said leg-rest and guiding the same for movement between a retracted position beneath the forward end of the seat and an elevated position forwardly of the seat, and an actuating link connecting said intermediate link with said leg-rest mounting linkage, said one carrier link being moved rearwardly by said rear guide link, as the latter turns during the first motion phase, to turn said intermediate link in a direction to actuate said leg-rest mounting linkage such that the leg-rest is brought to its elevated position, said carrier linkage being raised by said front guide link during said second motion phase to maintain said leg-rest substantially in its elevated position.

2. A multiple position reclining chair comprising a support frame, a body-supporting structure including a seat and back-rest, control means mounting the body-supporting structure on the support frame for movement through a first motion phase from a sitting position to an intermediate, tilted sitting position and through a second motion phase from said intermediate, tilted sitting position to a reclining position, said control means including front and rear guide links pivotally connected to spaced points on the seat, the rear guide link having a pivotal mount on the support frame, and a carrier linkage mounting the front guide link, said carrier linkage including a pair of carrier links extending forwardly of the chair, and an intermediate link pivotally connected to the forward ends of said carrier links and extending therebetween, at least one of said carrier links being pivotally mounted on the rear guide link for rearward axial movement of said one carrier link when the rear guide link turns rearwardly during the first motion phase, said front guide link being pivotally mounted on a link of said carrier linkage, the front guide link turning rearwardly on the carrier linkage and the rear guide link turning rearwardly about its pivotal mount on the support frame during the first motion phase to guide the body-supporting structure rearwardly to the intermediate, tilted sitting position, stop means for halting rearward movement of the front and rear guide means relative to the carrier linkage at said intermediate, tilted sitting position, a leg-rest, a leg-rest mounting linkage mounting said leg-rest linkage on the seat and guiding the same for movement between a retracted position beneath and an elevated position forwardly of the seat, and means connecting said intermediate link to said leg-rest mounting linkage, the axial rearward movement of said one carrier link during the first motion phase turning said intermediate link in a direction to cause the latter to exert an actuating force on the leg-rest mounting linkage for elevating said leg-rest to its elevated position in the intermediate, tilted sitting position, said carrier linkage being raised by said front guide link during said second motion phase to maintain said leg-rest substantially in its elevated position.

3. A multiple position reclining chair comprising a support frame, a body-supporting structure including a seat and back-rest, control means mounting the body-supporting structure on the support frame for movement through a first motion phase from a sitting position to an intermediate, tilted sitting position and through a second motion phase from said intermediate, tilted sitting position to a reclining position, said control means including front and rear guide links pivotally connected to spaced points on the seat, the rear guide link having a pivotal mount on the support frame, and a carrier linkage mounting the front guide link, said carrier linkage including a pair of carrier links extending forwardly of the chair, and an intermediate link pivotally connected to the forward ends of said carrier links and extending therebetween, at least one of said carrier links being pivotally mounted on the rear guide link and slidably supported by said support frame for rearward axial movement of said one carrier link when the rear guide link turns rearwardly during the

first motion phase, said front guide link being pivotally mounted on a link of said carrier linkage, the front guide link turning rearwardly on the carrier linkage and the rear guide link turning rearwardly about its pivotal mount on the support frame during the first motion phase to guide the body-supporting structure rearwardly to the intermediate, tilted sitting position, stop means for halting rearward movement of the front and rear guide means relative to the carrier linkage at said intermediate, tilted sitting position, the carrier linkage thereafter being raised by said body-supporting structure from its slidably-supported position and the body-supporting structure turning about the rear guide link during the second motion phase, a leg-rest, a leg-rest mounting linkage mounting said leg-rest linkage on the seat and guiding the same for movement between a retracted position beneath the seat and an extended position forwardly of the seat, said intermediate link having an extension projecting beyond one of its pivotal connections with said carrier links, and an actuating link connecting said extension to said leg-rest mounting linkage, the axial rearward movement of said one carrier link during the first motion phase turning said intermediate link in a direction to cause said actuating link to exert an actuating force on the leg-rest mounting linkage for elevating said leg-rest to its extended position in the intermediate, tilted sitting position, said carrier linkage being raised by said front guide link during said second motion phase to maintain said leg-rest substantially in its elevated position.

4. A multiple position reclining chair according to claim 3 in which said one carrier link is pivotally mounted on the rear guide link and the other carrier link is pivotally mounted on the support frame.

5. A multiple position reclining chair according to claim 3 in which both carrier links are pivotally mounted on the rear guide link.

6. A multiple position reclining chair according to claim 3 in which said carrier links are vertically spaced, the uppermost carrier link being pivotally mounted on the support frame and the lowermost carrier link being pivotally mounted on the rear guide link, the extension of said intermediate link projecting above the pivotal connection between the intermediate link and the uppermost carrier link, said intermediate link being turned in a direction to move said extension and actuating link forwardly.

7. A multiple position reclining chair according to claim 3 in which said carrier links are vertically spaced, both carrier links being pivotally mounted on the rear guide link, the extension of said intermediate link projecting above the pivotal connection between the intermediate link and the uppermost carrier link, said intermediate link being turned in a direction to move said extension and said actuating link rearwardly during the first motion phase.

8. A multiple position reclining chair according to claim 7 in which said leg-rest is carried by a leg-rest mounting linkage pivotally mounted on said seat, one of the mounting linkage links having an upstanding exten-

sion projecting beyond its pivotal mount on the seat, said actuating link connecting said mounting link extension to the extension of said intermediate link.

9. A multiple position reclining chair according to claim 3 in which both carrier links are pivotally mounted at spaced points on the rear guide link, said carrier links crossing each other and the forward ends thereof being pivotally connected to spaced points on the intermediate link.

10. A multiple position reclining chair comprising a support frame, a body-supporting structure including a seat and back-rest, control means mounting the body-supporting structure on the support frame for rearward movement through a first motion phase from a sitting position to an intermediate, tilted sitting position and through a second motion phase to a reclining position, said control means including front and rear guide links pivotally connected to spaced points on the seat, the rear guide link having a pivotal mount on the support frame, and a carrier linkage mounting the front guide link, said carrier linkage including a pair of carrier links extending forwardly of the chair and an intermediate link pivotally connected to the forward ends of said carrier links and extending therebetween, at least one of said carrier links being pivotally mounted on the rear guide link, said one carrier link being slidably mounted on said support frame for longitudinal movement during said first motion phase, said carrier linkage constituting multiple linkage during the first motion phase, including said rear guide link as a movable link thereof, a leg-rest, a leg-rest mounting linkage carrying said leg-rest and guiding the same for movement between a retracted position beneath the forward end of the seat and an elevated position forwardly of the seat, and an actuating link connecting said intermediate link with said leg-rest mounting linkage, said one carrier link being moved rearwardly by said rear guide link, as the latter turns during the first motion phase, to turn said intermediate link in a direction to actuate said leg-rest mounting linkage such that the leg-rest is brought to its elevated position, stop means for halting movement of the rear guide link at the intermediate, tilted sitting position, such that the carrier linkage becomes a four-bar linkage during the second motion phase with the carrier links and the intermediate link constituting the movable links thereof, the movable links of said four-bar carrier linkage being raised during the second motion phase by said front guide link to maintain said leg-rest substantially in its elevated position.
